CAR END STRUCTURE

Mark H. Martin, Reading, Pa., assignor to Birdsboro Steel Foundry & Machine Company, Birdsboro, Pa., a corporation of Pennsylvania

Application November 11, 1932, Serial No. 642,204

2 Claims. (Cl. 195—403)

5 My invention relates to a car end structure and more particularly to an integral casting which is adapted for application and securement to the ends of the principal under-framing of the car, as well as, in certain types of cars, such as box cars and the like, to the upper-framing as well.

One object of my invention is to provide an 10 integral casting of the character indicated which comprises the customary end sill and integrally formed therewith cheek plates which are fashioned for attachment to the draft or center sills of the car and each of which is provided with a pair of aligned slots for the reception of the front and rear draft keys of a standard type of draft gear employing a horizontal yoke.

15 A further object is to devise an integral casting as above stated in which the end sill, in addition to incorporating integral cheek plates having aligned draft key slots, is also provided with integral portions adapted to act as the coupler striker and the carry iron for the draw bar of the coupler.

20 A further object is to devise an end structure for gondola cars wherein the integral end sill and cheek plate casting is further provided with flanges for attachment to the side sills of the car and is also integrally formed with corner posts which provide rigid anchorages for the sides and 25 ends of the car body, as well as incorporating flanges for direct attachment thereto of the side sheets.

25 A further object is to provide an end structure for cars having end doors which includes a marginal door framing arranged to act as the structural basis for the end of the car and to substantially immobilize the margin of the door opening by preventing the transmission of racking strains to the doors, the door framing being provided with flanges for direct attachment to the roof and 30 side sheets, and the side plates, and being integrally formed with an end sill which is provided with cheek plates adapted to cooperate with the draft keys of a draft gear utilizing a horizontal yoke.

35 An integral casting of the foregoing character embodies in a single unit a variety of individual elements which are now riveted to each other in order to build up the complete end structure. It is extremely difficult and practically impossible 40 to maintain the integrity of a car end formed of riveted parts against the buffing and surging stresses encountered in train operation and, as principal reliance is placed upon the car end structure to protect the remaining portions of 45 the car body against racking strains, it is most important that some device be provided which will strengthen and rigidify the end of the car and which will effectually resist these service shocks.

50 The integral casting disclosed in this applica-

5 tion effectually solves the foregoing problem, particularly when employed in connection with draft gears employing twin sets of draft keys, i. e., gears of the horizontal yoke type. With such gears, it is contemplated that the end sill will have integrally formed therewith a pair of cheek plates which are adapted for attachment to the draft sills of the car and each of which includes a pair of aligned slots for the reception of the front and rear draft keys. By such an arrangement, it 10 is possible to effect a more efficient and stronger connection of the end structure with the draft sills, as well as securing a better alignment of the key slots, so that a more accurate coordination of the draft keys with the other portions of 15 the draft gear is secured.

Two types of car end structures are described in the present application, one being intended for use in connection with box cars having end doors, and the other for attachment to the ends of 20 gondola cars. In the former case, the end casting preferably includes a marginal framing which is arranged to receive the end doors, as well as to have directly attached thereto the roof and side sheets and the side plates located under the 25 roof eaves, while in the gondola end structure, the end casting has integrally formed a pair of rigid corner posts upon which primary dependence is placed to resist the bulging strains against the car sides and to which the side sheets are 30 directly attached. In each type of casting, whether for gondola or box cars, the integral end sill is further provided for attachment directly to the side sills and also integrally incorporates portions intended to function as the 35 coupler striker and the carry iron for the coupler draw bar.

These and further objects of my invention will be set forth in the following specification, reference being had to the accompanying drawings, 40 and the novel means by which said objects are effectuated will be definitely pointed out in the claims.

In the drawings:

Figure 1 is an end elevation of one form of my 45 improved car end structure which is intended for attachment to the ends of box cars provided with end doors.

Fig. 2 is an enlarged section taken along the line 2—2 in Fig. 1, looking in the direction of the 50 arrows, and showing the relation of the integral cheek plates and the draft sills of the car.

Fig. 3 is an enlarged plan view, partly in section, of the central portion of the end sill, as viewed in the direction of the arrow 3 in Fig. 2, showing 55 the relation of the end casting to the associated parts of a draft gear having a horizontal yoke.

Fig. 4 is a section along the line 4—4 in Fig. 2, looking in the direction of the arrows, and showing the manner in which the cheek plates overlie 60

the web portions of the draft sills, with the marginal flanges of the key slots in the plates extending through appropriate slots in the sills.

Fig. 5 is an elevation of an end structure for use 5 with gondola cars, showing the corner posts integral with the end sill.

Fig. 6 is an enlarged section along the line 6—6 in Fig. 5, looking in the direction of the arrows, and showing the relation of the integral 10 cheek plates to the draft sills.

Fig. 7 is a plan view of the central portion of the end sill, corresponding generally to the view shown in Fig. 3, the major portion of the draft gear being omitted.

Fig. 8 is an enlarged elevation of the lower end 15 of the casting, as viewed in the direction of the arrow 8 in Fig. 5.

Referring to Figs. 1 to 4, inclusive, the numeral 10 designates one form of my improved end structure which is intended for application to the end 20 of a box car employing end doors, and which comprises a one-piece casting including an end frame 11 and an end sill 12. The frame 11 comprises a pair of legs 13, 13 which extend upwardly 25 from the ends of the sill and each leg is formed with a marginal plate portion 14 that is flanged as at 15 on its outer edge for stiffening and on which plate portions are formed hinge lugs 16 intended for the carriage of the end doors. The 30 legs 13 are connected at the top by a cross member 17 which also includes a marginal plate portion 18 that is flanged inwardly as at 19 for direct attachment thereto of the roof sheets 20. Preferably, the upper edge of the portion 18 slopes 35 downwardly at any convenient angle from the ridge line of the roof. A continuous, integral flange 21 extends inwardly from the inner edges of the plates 14 and 18 to form the vertical flanges 22, 22 and the upper, horizontal flange 23, so 40 that the vertical and upper plate portions possess generally a channel section.

The junctions of the upper ends of the flanges 22 and 23 are preferably curved as at 24 to fit the customary type of doors employed, while an 45 auxiliary extension 25 is provided on each end of the flange 23 for connection with a similar extension 26 formed as a continuation of the upper ends of the flanges 22. There is thus 50 formed a square corner at each upper end of the legs 13 for the reception of one end of a side plate 27 that is substantially a Z-bar in section, as shown clearly in Fig. 1. The web portion of 55 the side plate rests on the extension 25, while the upper, vertical flange is secured to the outermost rib 28, several of such ribs being located between the flanges 19 and 23, and the ends of the roof sheet 20 are bent down and over these vertical flanges and riveted thereto. The lower vertical flange of the plate 27 extends downwardly along 60 the extension 26, but is spaced slightly therefrom to permit the securing therebetween of the upper corner of the side sheet 29. The vertical edge of 65 said sheet is secured in overlapping relation to the flange 22 along the length thereof, as shown in Fig. 1. The lower portion of the continuous flange 21 projects from the end sill 12 to form a beveled portion 30 (see Fig. 2) which slopes downwardly and outwardly from the interior of the car to constitute a threshold.

70 The foregoing portions of my improved end structure are substantially identical with those disclosed in my United States Letters Patent, No. 1,850,283, dated March 22, 1932, but have been adverted to in the present instance as showing the manner in which such an end frame can be as-

sociated with an end sill provided with cheek plates adapted to coact with a draft gear of the horizontal yoke type.

The end sill 12 is formed as an integral casting with the door framing and includes upper and 5 lower flanges 31 and 32, respectively, which are joined by a connecting web 33. Strengthening ribs 34 may be disposed at appropriate intervals between said flanges and an extension 35 projects upwardly as a continuation of the web 33 10 to merge into the threshold 30, as shown in Fig. 2. As indicated in my earlier patent, the threshold 30, together with the continuous, integral flange 36 that extends along the legs 13 and cross member 17 normal to the flanges 21 and 23, respectively, forms a seat for the doors which are 15 customarily of the double variety.

The depth of the web 33 is increased at the midportion of the sill and extends forward from the vertical plane thereof to form a projection 37. 20 A passage 38 extends through said projection for the reception of the draw bar 39 of a coupler (not shown). Above the opening 38, the projection 37 is generally channel-shaped in section, as shown in Fig. 2, with the upper limb 40 thereof being a continuation of the upper flange 31 and the vertical web 40 being substantially flush with the upper, front side of the projection 37 and serving as a striker for the horns of the coupler. Below the opening 38, the projection 30 37 is also generally channel-shaped in section with the front limb 41 thereof being substantially flush with the lower portion of the projection 37, but preferably located inwardly of the surface of the striker 40, with the horizontal web 35 42 serving as a carrier for the draw bar 39.

The outer, vertical edges of the opening 38 are defined by the flanges 43 which extend toward each other, as shown in Fig. 3, for the purpose 40 of limiting the swinging movement of the coupler when the car is rounding curves and to generally strengthen this portion of the structure against the impact of the draw bar during such movement. The flanges 43 are connected by means 45 of webs 44 to the vertical web 33 of the end sill and extending inwardly from said last-named web in substantial alignment with the web 44 is a pair of cheek plates 45. These plates are cast integrally with the end sill and each is provided with a front slot 46 and a rear slot 47 which are 50 aligned with each other and intended for the reception of front and rear draft keys 48 and 49, respectively, both of said keys also extending through appropriate slots provided in a horizontal yoke 50 that is suitably associated with a 55 draft gear generally denoted by the numeral 51. Each of the key slots is defined by a continuous flange 52 that extends laterally of the cheek plates in each direction and these key slots fit closely within open-ended slots 53 provided in 60 the adjacent draft sills 54. Rigid attachment between the draft sills and the cheek plates is provided by means of rivets 55. The relation between the slots in the draft sills and the marginal flanges around the slots in the cheek plates 65 not only provides for an easy and convenient assembly of these parts, but also by reason of the substantial interlocking of the slot flanges with the draft sills insures a general strengthening 70 of this portion of the car construction.

As a further strengthening provision, the depth of the upper flange 31 of the end sill is increased as at 56 over the draw bar and this depth extension is integrally formed with the cheek plates 45, as shown clearly in Fig. 4, the outer edges 75

of the extension projecting through slots 57 provided in the draft sills and bending downwardly on the outside of the vertical webs of said sills to form the cheek plates. The flange 58 also 5 provides a convenient point of attachment for the end of the cover plate 56* overlying the draft sills.

At each end of the end sill, a vertical flange 58 is provided for direct attachment to the adjacent ends of the side sills 59. The lower ends 10 of the side sheets 29 are also secured to the flanges 58.

According to the above invention, therefore, a structure is provided that is susceptible of being 15 tied to the principal framing of the car and which is particularly adaptable for use in connection with cars provided with draft gears having horizontal yokes. The end structure is capable of being cast in one piece for direct attachment to the end of a car, with obvious advantages resulting from the simplification of assembly problems inherent in the handling of a single piece, as contrasted with a multiple of parts as is now common in the building of an 20 end structure formed of numerous parts which are riveted together. One of the principal advantages of the structure is the manner in which the cheek plates are associated with the draft sill for the purpose of generally strengthening the 25 car in this location and also the positive assurance that is had from an incorporation within a single casting of the twin slots for the draft keys. Such an arrangement insures an accurate alignment of the draft keys and therefore a most 30 efficient transmission of the draw bar pull to the car, free of any undue strain on the draft gear parts.

In the modification, illustrated in Figs. 5 to 8, inclusive, the numeral 60 designates an end structure which is more particularly intended for use 40 in connection with a gondola car and which comprises an end sill 61 and corner posts 62, all integrally cast together, with the corner posts functioning as the principal support for the sides 45 of the car, in conjunction with the usual side stakes. As indicated, each corner post is generally of angle shape in horizontal cross-section, and comprises vertically disposed wings 63 and 64 which are tied together at their upper ends by a 50 cap 65. Extending outwardly from each corner post is a flange 66 that is united with the adjacent wing 64 by means of a rib 67. The flange 66 is intended for the direct attachment thereto of one 55 end of a bar 68 which defines the top edge of the side of the car. Each wing 64 may be also apertured as at 69 for the purpose of receiving rivets as a means of attaching the side sheets of the car to the corner post. The lower end of the corner post may be substantially enlarged as at 70, 60 as a continuation of the wing 64, to provide for the attachment of the side sill 71 and such other side members as may be desirable.

The end sill 61 is generally of channel section and comprises an upper flange 72 and a lower 65 flange 73, both of which are connected by a vertical web 74. The central portion of the end sill, that is, the part which includes the opening through which the coupler draw bar extends, is generally of the same construction as explained 70 in connection with the modification shown in Fig. 1. In other words, it includes a draw bar opening 75, a carry iron portion 76, a coupler striker 77, and integral cheek plates 78 that extend rearwardly from the end sill in substantially

the same relation thereto as shown in Fig. 1. It will be unnecessary, therefore, to discuss this portion of the end casting in any detail.

An abutment flange 79 extends upwardly from the end sill flange 72 intermediate the side edges thereof and is intended to operate as a partial backing for that type of door in gondola cars which swings inwardly of the car to lie flat on the floor thereof, thus opening the ends of the car and permitting the carriage of girders, or other articles having a length greater than the length of the car. This abutment flange is tied into the end sill in a manner to generally strengthen the casting in this locality and it extends transversely of the car for integral merging 15 with the corner posts. The flange 72 is extended inwardly of the car beyond the abutment flange 79 to form a flange 80 that is located centrally of the end sill and to which the draft sill cover plate 81 is attached. The ends of the flange 80 merge 20 into the cheek plates 78 in a manner generally similar to that illustrated in Fig. 4.

An end casting of the type shown in Fig. 5 possesses generally the same advantages as have been set forth in connection with the box car type 25 of end structure, but, in addition, possesses several important advantages which are peculiar to this type of car. In gondola cars, the corner posts are the principal point of weakness, since the resistance of the car sides to bulging forces 30 largely depends upon the strength of the corner post construction. These bulging forces are, of course, accentuated by the buffing action of the coupler, so that it is important to provide an end casting that will not only efficiently contain the 35 static lading through a proper corner post construction, but will also tie in this portion of the end casting with other portions thereof, and, in particular, with the draft sills.

I claim:

1. In car construction, the combination of a pair of spaced draft sills, each having an elongated slot in the vertical web thereof and a laterally directed flange including a slot adjacent its upper edge, and a car end structure formed as a 45 one-piece casting comprising an end sill, uprights at the ends of said sill for attachment to the side sheets, cheek plates integral with said sill for attachment to the draft sills, each plate including a pair of aligned slots for receiving 50 the draft keys of an associated draft gear, and each of said aligned slots being defined by a marginal flange extending laterally of the associated cheek plates for fitting within the slots of said draft sills, and a flange connecting said cheek 55 plates through the slots in the sill flanges and adapted for attachment to the cover plate for the draft sills.

2. In car construction, the combination of a pair of spaced draft sills, each having an elongated slot in the vertical web thereof and a laterally directed flange including a slot adjacent its upper edge, and a car end structure formed as a one-piece casting comprising an end sill, cheek plates integral with said sill for attachment 65 to the draft sills, each plate including a pair of aligned slots registering respectively with the slots in the sills for receiving the draft keys of an associated draft gear, and a flange connecting said cheek plates through the slots in the sill flanges 70 and adapted for attachment to the cover plate for the draft sills.

MARK H. MARTIN.
